(57) **CLAIM**

The ornamental design for a chair, as shown and described.

DESCRIPTION

FIG. 1 is a top front isometric view of a chair showing our new design.

FIG. 2 is a top plan view thereof.

FIG. 3 is a bottom plan view thereof.

FIG. 4 is a left-side elevation view thereof; and,

FIG. 5 is a right-side elevation view thereof.

The dashed dot lines immediately adjacent to the shaded areas in the figures represent the boundaries of the claimed design. The dashed lines in the figures illustrate the portions of the design that form no part of the claimed design. None of the broken lines form any part of the claimed design.
